SHEET REGISTERING MECHANISM

Frank R. Belluche, Racine, Wis., assignor to The Christensen Machine Company, Racine, Wis., a corporation of Wisconsin

Application May 31, 1943, Serial No. 489,176

15 Claims.

(Cl. 271—53)

This invention relates to improvements in sheet registering mechanism for printing presses and the like and has particular reference to means for reregistering sheets after they have been picked up by the receiving cylinder of the press which may be a transfer cylinder or an impression cylinder as in a flat bed press.

Sheets fed to a printing press or other like machine are front registered by the feeder advancing them to the usual front guide. Thus, at the instant the sheets are presented to the cylinder they are in proper front registry. At that instant, however, the sheets are at rest while the cylinder is rotating, often at a high speed. Hence, when the grippers on the cylinder take hold of the sheet slippage is inevitable, due to the necessity of bringing the stationary sheet up to the cylinder speed.

The amount of this slippage is dependent upon the speed of the cylinder. If the cylinder speed is constant the extent of the slippage is uniform and thus its presence is not too serious. A uniform slippage can be compensated for, but any change in the cylinder speed alters the degree of slippage and results in faulty registry of the sheet.

This invention, therefore, has as its principal object the provision of means for effecting a re-registration of the sheet after it has been picked up by the transfer or receiving cylinder and while it is moving with the cylinder so that regardless of the extent or variation of the slippage, the sheet always occupies a predetermined position on the cylinder.

Inasmuch as the correction of the position of a sheet on the cylinder entails releasing it from the grippers, it is another object of this invention to provide means for momentarily reopening the grippers in time for reregistering means to function, and also to provide other means for holding the sheet on the cylinder during this interval.

Another object of this invention is to provide several different ways of effecting the desired re-registration which involve either moving the sheet with respect to the cylinder into engagement with a front register face fixed on the cylinder or moving the register face into engagement with the front edge of the sheet and thereafter shifting the position of the sheet to a predetermined location at all times accurately defined.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best

modes so far devised for the practical application of the principles thereof, and in which:

Figure 1 is a fragmentary view of a mechanism embodying this invention and illustrating the same at an instant in the cycle directly after the sheet has been taken by the grippers;

Figure 2 is a view similar to Figure 1 illustrating the grippers opened slightly and the sheet being reregistered;

10 Figure 3 is a view similar to Figures 1 and 2 showing the grippers closed again and the re-registering mechanism inoperative;

15 Figure 4 is a fragmentary view similar to Figure 1 of a modified embodiment of this invention wherein a moving suction gripper takes hold of the sheet and advances it into engagement with a front registry face;

Figure 5 is a fragmentary view also similar to Figure 1 of another modification of this invention;

20 Figures 6, 7 and 8 illustrate still another form of this invention;

25 Figure 9 is a view diagrammatically illustrating the manner in which a sheet is properly registered by the front guide at the instant the grippers close down onto it;

Figure 10 is a view similar to Figure 9 illustrating the occurrence of slippage which it is the purpose of this invention to correct; and

30 Figure 11 is a view diagrammatically illustrating the reopening of the grippers and indicating the interval in the cycle during which the re-registration of the sheet is effected.

Referring now more particularly to the accompanying drawings, in which like numerals indicate like parts, the numeral 4 designates the feed or transfer cylinder of a printing press or other machine intended to perform work on sheet material and which constantly revolves to carry 35 sheets into the machine as they are presented thereto.

The sheets S may be advanced to the transfer cylinder 4 in any suitable manner. In conventional practice the sheets S are advanced by an 40 automatic sheet conveyor until their front edges strike a front guide 5 which momentarily stops the advance of the sheets and front registers them before presenting them to the transfer cylinder.

45 Grippers 6 controlled by tumbler mechanism (not shown) and carried by the transfer cylinder 4 take hold of a sheet at rest at the front guide and advance it to the printing couple of the press.

50 As diagrammatically illustrated in Figure 10 and as explained hereinbefore, during the operation of the conventional printing press or other similar machine the abrupt change of a sheet at rest at the front guide to a sheet moving at press speeds causes slippage of the sheet in the bite of the grippers to an extent depending upon the

55 60

speed of the press. The present invention overcomes the objections to this slippage by restoring the sheets to a predetermined position on the cylinder regardless of the existence or extent of this slippage.

In carrying the invention into practice two broad classes of apparatus may be employed. In the one case illustrated in the two embodiments of the invention shown in Figures 1 to 4, inclusive, the cylinder has a fixed abutment 7 providing a front registry face or guide with which the front edge of the sheet is engaged by the operation of the reregistering mechanism.

In the other broad class of apparatus illustrated in Figures 5 to 8, inclusive, the cylinder carried registry face 8 is movable with respect to the cylinder and the sheet on it, but the mechanism embodies means for positively and accurately defining a fixed position of the registry face after it has engaged the sheet to insure the sheet being in a predetermined position on the cylinder.

Considering first that form of the invention illustrated in Figures 1 to 3, inclusive, it will be noted that the abutment 7 which provides the front registry face is so positioned that the sheet taken by the grippers 6 is spaced a slight distance therefrom due to the slippage occurring at the instant the sheet is picked up. At that instant, the front edge portion of the sheet directly overlies the lower jaw 9 of an auxiliary gripper or gripping device indicated generally by the numeral 10.

This auxiliary gripping device may consist of a plurality of grippers extending across the cylinder and each comprising a lower jaw 9 and a movable upper jaw 11 hingedly connected as at 12.

The entire auxiliary gripper assembly is movable with relation to the cylinder and is constrained to a given motion by guides 13 at opposite ends of the cylinder, only one of which is shown. The guides 13 may be in the form of box cams receiving cam followers 14 and, as will be observed from a comparison of Figures 1, 2 and 3, so guide the motion of the gripper assembly as to have the same move a short distance along the path of the sheet and then inwardly or downwardly out of the path of the sheet.

The motion of the auxiliary gripper mechanism is cam produced. A stationary cam 15 at one end of the cylinder is engaged by a follower 16 as the cylinder rotates. The follower 16 is on a lever 17 connected to the gripper mechanism as at 18 and mounted on a fixed pivot 19. A spring 19' insures the follower 16 following the cam.

The opening and closing of the auxiliary grippers is controlled by another fixed cam 20 with which a cam follower 21 engages. The cam follower 21 is carried on one arm of a bell crank lever 22 having a fixed pivotal connection 23 with the cylinder and having its other arm 24 projecting into the path of a finger 25. The finger 25 has a fixed connection with the movable gripper 11, and a spring 26 biasing the movable gripper to its closed position insures engagement of the finger 25 with the lever arm 24.

In the position of the parts shown in Figure 1, the main grippers 6 are closed and the sheet has its front edge spaced from the registry face of the abutment 7. During the next few degrees of cylinder rotation the main grippers 6 are opened in the manner diagrammatically illustrated in Figure 11 and during this interval the cam follower 21 leaves the cam 20 allowing the auxiliary grippers to close onto the sheet.

The next instant the cam follower 16 riding up onto the cam 15 advances the auxiliary gripper mechanism to pull the sheet forwardly into engagement with the abutment 7. The lightness of the bite with which the sheet is held in the auxiliary grippers permits overtravel of the auxiliary grippers beyond the point at which the front edge of the sheet engages the registry face of the abutment 7. The auxiliary gripper thus merely continues its advance and slips off the front edge of the sheet, and at that instant the main grippers reclose and hold the sheet in proper reregistered position on the cylinder.

In that embodiment of the invention illustrated in Figure 4 the sheet is advanced into engagement with the registry face of the abutment 7 by a swinging suction member 27. This suction member is pivoted as at 28 to the cylinder and is biased to swing toward the abutment 7 by a spring 29.

20 The mouth 30 of the suction member swings in an arc tangent to the path of the sheet advance so that a sheet gripped thereby will be properly advanced into engagement with the abutment 7 under the control of a cam 31. The cam 31 is provided with a depression into which a cam follower 32 carried by the suction member rides to release the suction member for sheet advancing movement under the influence of its spring 29.

It is, of course, understood that the application of suction is timed with the cam controlled motion of the suction member to come on at the right instant and to release after the main grippers have reclosed and before the cam 31 swings the suction member back to its retracted position shown in dotted lines.

30 In this instance the suction member performs the dual function of advancing the sheet into engagement with the abutment 7 and also holding it onto the cylinder during the interval the main grippers are open.

35 In this instance the suction member performs the dual function of advancing the sheet into engagement with the abutment 7 and also holding it onto the cylinder during the interval the main grippers are open.

40 That embodiment of the invention illustrated in Figure 5 falls into the second designated broad class in that its registry face 8 is movable. The registry face 8 is on the outer end of a lever 33 pivoted to the cylinder as at 34. An actuator 35 for the lever 33, is also pivoted at 34. This actuator has an impositive driving connection with the lever provided by a spring 36 by which the lever member 33 is swung from its inactive position (shown in dotted lines) toward the front edge of the sheet to engage the same and come to rest against a fixed stop 37. The stop 37 accurately defines the registry position of the lever 33.

45 A positive driving connection is also provided between the actuator and the lever. This connection consists of an arm 38 which projects over the lever 33 to engage the same and swing the lever back to its inactive position indicated in dotted lines and defined by a fixed stop 39. The motion of the actuator to return the lever in this manner is produced by a spring 40.

50 A cam follower 41 on the outer end of the actuator is in position to engage a stationary cam 42 and effect the functioning of the mechanism as the cylinder revolves.

55 During the interval the reregistering is effected the main grippers are, of course, open and during this time the sheet is held against displacement from the cylinder by a suction nozzle 43 which grips the sheet at a distance back from its front edge. The suction to this nozzle is controlled to come on just before the main grippers open and to go off right after the main grippers reclose.

75 While the embodiment of the invention shown

in Figures 6 to 8, inclusive, falls into the same class as that just described, in that the registry face is movable, in this case the proper registry position is defined by arresting forward motion of a combined auxiliary gripper and registry member 44 at an accurately defined location.

The member 44 is pivoted as at 45 to the cylinder. At its outer end it has an auxiliary gripper comprising a lower jaw 46 and an upper jaw 47 hingedly connected at 48 and biased to closed position by a spring 49. A front registry face 50 extends across the bite of these jaws to engage the front edge of the sheet during operation. The movable gripper jaw 47 has an actuator arm 51 connected thereto and on the end of this arm is a cam follower 52 engageable with a cam 53 to control opening and closing of the auxiliary gripper.

The combined auxiliary gripper and registry member 44 is swung on its pivot by an actuator 54 similar to the actuator shown in Figure 5. As in the manner described in connection with Figure 5, the actuator 54 is controlled by a stationary cam 55 to impositively swing the member 44 toward the front edge of the sheet and positively swing the member 44 in the opposite direction.

In this instance, however, the parts are so co-related that as the member 44 is swung toward the front edge of the sheet being held by the main grippers, the jaws 46 and 47 are open to close down onto the sheet after the registry face 50 has engaged its front edge. At this point the main grippers open. This is the position of the parts shown in Figure 6.

During the next few degrees of cylinder travel the cam follower on the actuator 54 rides off the cam 55 (as shown in Figure 7), and the actuator impelled by its spring swings the member 44 in the direction of sheet advance pulling the sheet with it until an arm 56 on the lever member 44 engages a releasable latch 57.

The latch 57 consists of a bell crank lever pivoted at 58 and held in an active position defined by a fixed stop 59 by a spring 60.

As the arm 56 comes up against the latch 57 the advance of the sheet by the auxiliary grippers is arrested—always at the proper position—and during the next instant the main grippers reclose and the auxiliary grippers are opened by the cam follower 52 riding up onto the cam 53 as shown in Figure 7.

At this point the reregistering of the sheet has been completed and it requires merely the withdrawal of the reregistering mechanism from the path of the sheet. This occurs after release of the latch 57 by a cam follower 61 on the latch riding up onto the cam 55 as shown in Figure 8.

It is, of course, to be understood that the reregistering mechanism in each of the several embodiments of the invention herein described is arranged at least in duplicate with one such set of mechanism near each end of the cylinder and preferably adjustable as to its position lengthwise of the cylinder to accommodate sheets of different widths and maintain the same square on the cylinder as their reregistration is effected.

From the foregoing description, taken in connection with the accompanying drawings, it will be readily apparent to those skilled in the art, that this invention provides an effective and simple manner of overcoming the objections inherent in all past receiving and transfer cylinders of printing presses resulting from the inevitable slippage of the sheet in the bite of the grippers as the sheet is picked up and abruptly brought

from a position of rest to the speed of the rotating cylinder.

What I claim as my invention is:

1. In a sheet carrying cylinder for printing presses and the like: grippers carried by the cylinder adapted to grip and hold a sheet presented thereto, on the cylinder; means for momentarily reopening the grippers after they have closed; and means on the cylinder for reregistering a sheet on the cylinder during the interval of momentary reopening of the grippers.
2. In a sheet carrying cylinder for printing presses and the like: grippers on the cylinder to grip and hold a sheet fed to the cylinder, on the cylinder; means for momentarily reopening the grippers after they have gripped a sheet; a registry face carried by the cylinder; and means for holding the sheet on the cylinder and effecting engagement of its front edge with the registry face during the interval of momentary opening of the grippers.
3. In a sheet carrying cylinder for printing presses and the like: grippers on the cylinder to grip and hold a sheet presented thereto, on the cylinder; an abutment fixed with respect to the cylinder and providing a front registry face; means for momentarily reopening the grippers to release the sheet after the sheet has been initially gripped and while it is moving with the cylinder; and other sheet gripping means for gripping the sheet and moving the same into engagement with the registry face during the interval of momentary opening of the grippers.
4. In a sheet carrying cylinder for printing presses and the like: grippers on the cylinder to grip and hold a sheet presented thereto, on the cylinder; an abutment presenting a front registry face; means carried by the cylinder mounting the abutment for movement towards the front edge of a sheet on the cylinder; means for so moving the abutment to bring the same into engagement with the front edge of the sheet; means for accurately defining the limit of movement of the abutment toward the sheet to accurately define the front registry position; means for momentarily reopening the grippers to free the front edge of the sheet for engagement with the registry face; and means for holding the sheet on the cylinder during the interval of momentary opening of the grippers.
5. In a sheet carrying cylinder for printing presses and the like: grippers on the cylinder to grip and hold a sheet fed to the cylinder, on the cylinder; means for momentarily reopening the grippers after they have gripped the sheet and while the sheet is moving with the cylinder; a front registry face carried by the cylinder; auxiliary sheet gripping means for holding the sheet during the momentary opening of the grippers; and means for actuating the auxiliary sheet gripping means to effect engagement of the front edge of the sheet with the registry face for correcting possible faulty registration of the sheet.
6. In a sheet carrying cylinder for printing presses and the like: grippers on the cylinder to grip and hold a sheet fed to the cylinder; means for momentarily reopening the grippers after they have gripped the sheet and while it is moving with the cylinder; an abutment on the cylinder providing a registry face; auxiliary sheet gripping means for holding the sheet on the cylinder during the interval of momentary opening of the grippers; and cam controlled mechanism for advancing the auxiliary sheet gripping means to effect engagement of the front edge of the sheet

with the registry face and thus correct possible faulty front registry of the sheet.

7. In a sheet carrying cylinder for printing presses and the like: grippers on the cylinder adapted to grip a sheet presented thereto; means for momentarily reopening the grippers after the sheet has been gripped thereby; a registry face carried by the cylinder; means on the cylinder for gripping the sheet and advancing the same during the interval the grippers are open to effect engagement of its front edge with the registry face for correcting possible faulty registration of the sheet; and means for retracting said gripping means to an inoperative position after the sheet has been properly registered.

8. In a sheet carrying cylinder for printing presses and the like: grippers on the cylinder to grip and hold a sheet fed to the cylinder; means for momentarily reopening the grippers after the sheet has been gripped thereby; an abutment fixed with respect to the cylinder and providing a registry face to define the proper front registry position of the sheet; means for gripping the sheet and moving the same toward the abutment to effect engagement of the front edge of the sheet with the registry face during the interval the grippers are open; and means for subsequently moving said gripping means out of the path of the sheet.

9. In a sheet carrying cylinder for printing presses and the like: grippers carried by the cylinder to grip and hold a sheet presented thereto, an abutment presenting a front registry face; means movably mounting the abutment on the cylinder; means operable to bring the front registry face of the abutment into engagement with the front edge of the sheet; a stop carried by the cylinder for accurately defining the limit of movement of the abutment toward the sheet; means for momentarily reopening the grippers to free the front edge thereof for engagement with the registry face; and gripping means for holding the sheet on the cylinder during the interval of momentary opening of the grippers.

10. In a sheet carrying cylinder for printing presses and the like: grippers carried by the cylinder to grip and hold a sheet presented thereto; an abutment fixed on the cylinder and providing a front registry face; auxiliary grippers carried by the cylinder; means movably mounting said auxiliary grippers on the cylinder; means for constraining the motion of said auxiliary grippers to a path which follows the path of the sheet for a distance and then turns inwardly away from the path of the sheet; cam means for actuating the auxiliary grippers and for controlling opening and closing thereof so that the auxiliary grippers grasp a sheet on the cylinder to advance it into engagement with the front registry face; and means for momentarily reopening the main grippers during the interval the sheet is being advanced by the auxiliary grippers.

11. In a sheet carrying cylinder for printing presses and the like: grippers carried by the cylinder to grip and hold a sheet presented thereto; an abutment fixed with respect to the cylinder and providing a front registry face on the cylinder; an auxiliary suction gripper movably mounted on the cylinder to have its suction mouth reciprocable along the path of sheet advance; cam means for actuating the auxiliary suction gripper to move the same in a sheet advancing stroke at a speed in excess of that of the cylinder to advance a sheet gripped by said suction gripper into

engagement with the front registry face; and means for momentarily reopening the main grippers during the time the sheet is being advanced by said auxiliary suction gripper.

5 12. In a sheet carrying cylinder for printing presses and the like: grippers carried by the cylinder to grip and hold a sheet presented thereto, on the cylinder; a front registry member movably mounted on the cylinder and having a part thereof providing a front registry face; cam controlled means for moving said member to bring the registry face against the front edge of the sheet while it is held on the cylinder and moving therewith; means for accurately defining the limit 10 of said movement of the registry member; means for momentarily reopening the grippers to free the front edge of the sheet at the time it is engaged by said registry member; and suction means on the cylinder for holding the sheet there-to at a point spaced from its front edge during the 15 interval the grippers are momentarily open so that firm engagement between the registry member and the front edge of the sheet is assured.

13. Means for correcting possible faulty front 20 registering of a sheet on a cylinder of a printing press or the like while the sheet is moving with the cylinder, comprising: grippers on the cylinder to grip and hold a sheet presented thereto on the cylinder; cam means rendered effective by rotation of the cylinder for momentarily reopening the grippers to release the front edge of the sheet while the sheet is traveling with the cylinder; means for holding the sheet to the cylinder during the interval the grippers are reopened; a front 25 registry face carried by the cylinder; and cam controlled means rendered operative by rotation of the cylinder for bringing said front registry face and the front edge of the sheet into engagement, said cam controlled means being so timed 30 with relation to the cam means for momentarily reopening the grippers that the said engagement between the front registry face and the front edge of the face takes place during the interval the grippers are reopened.

40 14. In a sheet carrying cylinder for printing presses and the like: grippers on the cylinder to grip and hold a sheet presented thereto on the cylinder; a front registry face carried by the cylinder; means for momentarily reopening the grippers after they have closed on the sheet; other 45 means for holding the sheet on the cylinder during the interval the grippers are momentarily open; and means for effecting engagement of the front edge of the sheet with said front registry face during the interval the grippers are open and 50 while the sheet is being advanced by the cylinder to thus correct possible faulty registration of the sheet.

55 15. In a rotatable sheet carrying cylinder for printing presses and the like: sheet holding means 60 on the cylinder for holding a sheet presented thereto on the cylinder; a front registry guide carried by the cylinder; means for effecting momentary release of the sheet from said sheet holding means after said holding means has gripped the sheet and the sheet has started moving with the cylinder; other means for holding the sheet on the cylinder during the interval the sheet is not held by said first designated sheet holding means; 65 and means for effecting engagement of the front edge of the sheet with said front registry guide during said interval so that the sheet is front registered while it is being advanced by the cylinder.

FRANK R. BELLUCHE.
